A. W. Harris,

Treadle.

No 38,107.

Patented Apr 7, 1863

UNITED STATES PATENT OFFICE.

ABRAHAM W. HARRIS, OF PROVIDENCE, RHODE ISLAND.

IMPROVEMENT IN TREADLE-MOTIONS.

Specification forming part of Letters Patent No. 38,107, dated April 7, 1863.

To all whom it may concern:

Be it known that I, ABRAHAM W. HARRIS, of Providence, in the county of Providence, in the State of Rhode Island, have invented a new and improved mode of starting the crank-shaft of sewing-machine tables and preventing the same from being turned in the wrong direction; and I do hereby declare that the following is a full and exact description thereof, reference being had to the accompanying drawings, and to the letters of reference marked thereon.

The object which I accomplish with my invention is moving the crank of the driving-shaft of sewing-machine tables off the centers, and by the same device prevent the shaft from being turned in the wrong or opposite direction from which it is designed to rotate.

To enable others skilled in the art to make and use my invention, I will proceed to describe its construction and operation.

To illustrate my improvement more clearly, I will use the present form of the Wheeler & Wilson sewing-machine table. This table has a crank-shaft supported by the frame of the table. The crank of the shaft is connected by a pitman to a treadle which is operated by the foot and imparts the required motion to drive the machine, and when starting the shaft is as liable to be turned in the wrong direction as in the right; also, the crank is liable to stop on its center. To obviate these difficulties, I apply a vibrating arm on the straight part of the crank-shaft, having a pawl within it that produces a binding action on the shaft. I connect this vibrating arm to an independent treadle, *x*, by a pitman. This treadle is located on the same axis-rod as the crank-treadle. On the under side of this treadle, forward of the axis, is a stop, *y*, Figure 1, resting on the floor, the object of which is to hold the toe of the treadle in the position as shown and to prevent the vibrating arm from dropping down out of position. When the crank is on its center, by a gentle pressure of the foot upon the heel of the independent treadle a binding action of the pawl is produced on the shaft and moves the crank off the center. Thus the shaft is put in motion and in the right direction. The motion is then kept up by the crank-treadle, as in the ordinary manner. The pawl assumes its former position by slightly raising the foot from the heel and bearing upon the toe of the independent treadle and the assistance of a spring under the

heel of the treadle. It then remains at rest, ready to be thrown into action when required.

We will now suppose the crank to be in any position than on its center. If the power applied to the crank-treadle be not requisite to turn the shaft in the right direction, a binding action is produced upon the shaft by the pawl and the shaft will not turn. The operator is then necessarily compelled to apply the power in the opposite direction from which it was first applied. The shaft then being relieved of the binding action of the pawl, the crank moves in the right direction and the motion is kept up, as in the ordinary manner.

I will now proceed to describe how the binding action of the pawl is produced.

The vibrating arm *a*, Fig. 1, is fitted to the hub *b*, Fig. 3, which is secured to the crank-shaft. Through the vibrating arm *a*, Fig. 3, a circular slot is cut, the outer circle of which forms an inclined plane and the inner circle is formed by the outside of the hub *b*. In this slot, and in contact with the hub *b*, is a circular wedge, *c*, the inner circle conforming to said hub and the outer circle forming the wedge, and the incline thus formed stands opposite to the incline of the vibrating arm *a*, and between the two inclines is a roll, *d*. This roll is held in contact with the two inclined planes by means of a spring bearing against the end of the circular wedge. When the arm is moved upward, as indicated by the blue lines, Fig. 1, the roll binds between the two inclines and forces them apart, which creates a friction upon the hub *b*, and this being secured to the crank-shaft forces the shaft to rotate. The downward action of the arm *a* liberates the binding action of the roll *d* and allows the vibrating arm to turn freely on the hub *b*. A cap covers the slot in the vibrating arm, and is secured to the hub *b*.

I do not claim the roll *d* of the above-described pawl. Neither do I confine myself to any construction of pawls, nor the employment of a single-acting pawl.

Having thus described my invention, what I desire to secure by Letters Patent is—

A pawl or pawls acting by means of an independent treadle, in combination with the crank and crank-treadle of sewing-machine tables, as herein set forth.

ABRAHAM W. HARRIS.
